This is a continuation-in-part of my application for a patent for an auxiliary clothes line device, filed on June 21, 1940, Serial No. 341,783, and which is now pending.

UNITED STATES PATENT OFFICE

2,260,560

DEVICE FOR HANDLING AND SUSPENDING ARTICLES COLLECTIVELY

Marie Coleman, Haram Township, Bottineau County, N. Dak.

Application June 21, 1940, Serial No. 341,783

1 Claim. (Cl. 211—119.13)

This invention relates to clothes lines and more particularly to means for attaching clothes and similar articles to an ordinary clothes line, and has for the primary object the provision of a time saving device of this character which will permit articles of the kind specified to be conveniently applied in large numbers to an auxiliary line within a house and carried therefrom and easily and quickly attached to the ordinary clothes line in a collective manner so that the usual practice of attaching each article to the ordinary clothes line will be obviated and consequently eliminate a person spending long periods of time out-of-doors in cold weather in applying and removing articles from the ordinary or out-of-doors clothes line.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a perspective view illustrating the present invention supporting a plurality of articles on an ordinary clothes line and constructed in accordance with my invention.

Figure 2 is a perspective view illustrating one of the suspension hooks.

Figure 3 is a perspective view illustrating one of the auxiliary clothes line attaching hooks.

Figure 4 is a perspective view illustrating a plurality of articles arranged on the auxiliary clothes line and attached to a carrying medium.

Figure 5 is a side elevation illustrating one of the suspension hooks.

Figure 6 is a front elevation illustrating one of the suspension hooks.

Referring in detail to the drawings, the numeral 5 indicates an ordinary clothes line attached to supporting posts 6. It has been the present practice of attaching clothes and other articles onto the clothes line 5 by clothes pins wherein each article is applied and secured in a separate manner requiring a person to spend a considerable period of time in carrying out such operation out-of-doors. Of course, in cold weather this procedure is very undesirable and to eliminate the present practice, it is proposed to provide means for collectively securing a large number of clothes or other articles onto the clothes line in a quick and efficient manner.

An auxiliary clothes line is indicated by the

character 7 and has secured to its ends hooks 8 which are employed for securing the auxiliary clothes line in substantially parallelism with the clothes line 5 by engaging the hooks 8 in loops 9 formed in the clothes line 5 adjacent the posts 6. The various articles are secured on the auxiliary line 7 by conventional clothes pins 10.

Connected at spaced intervals to the auxiliary line 7 is a plurality of suspension hooks or members 11 which may be readily snapped onto the clothes line 5 after the connecting of the hooks 8 to the loops 9 to prevent undue sagging of the auxiliary line with respect to the clothes line 5. Further, the suspension members or hooks 11 are employed for connecting the auxiliary line with the articles applied thereto onto a carrying device 12 consisting of a bar or rod 13 and a bail 14. The bail 14 intermediate its ends is provided with a loop forming a handle 15. One end of the bail 14 is in the form of a keeper 16 into which one end portion of the bar 13 may be removably positioned while the other end of the bar is integrally connected to the other end of the bail by a tension forming loop 17. The tension forming loop 17 acts to retain the bar 13 in engagement with the keeper 16 in a safety pin fashion.

In use, the suspension hooks or members 11 are applied to the auxiliary clothes line 7 at spaced intervals and the articles of clothing are secured on the auxiliary line by the ordinary clothes pins 10. This entire operation is conveniently carried out within a house or laundry. Also, the rod 13 of the carrying device 12 is disengaged from the keeper 16 and then threaded through the suspending members 11 and reengaged with the keeper. The auxiliary clothes line with the articles applied thereto then can be conveniently carried by a person to the ordinary clothes line located out-of-doors. The various suspending devices are then removed one at a time from the carrying device and applied to the clothes line 5 and the hooks 8 applied to the loops 9 which completes the rapid and convenient manner of attaching a plurality of articles on the clothes line 5.

Each suspending member 11 consists of a shank 19 which has one end bent to form a double hook portion 20 through which the auxiliary line 7 may be laced, as shown in Figure 4. A portion 50 of the shank 19 is offset, as shown at 21, and then bent to form a tension forming loop or eye 22 and then bent to form a clasp portion 23 which coacts with the offset portion 21 in gripping the ordinary clothes line 5 or through which the bar 13 of the carrier may be passed. The

clasp portion 23 is urged in engagement with the shank 19 by the tension forming eye 22 so as to close the space between the clasp portion and the offset portion 21 of the shank. This space can be readily opened by flexing the clasp away from the shank to permit inserting of the ordinary clothes line 5 therein.

While I have shown and described the preferred embodiment of my invention, it will be understood that minor changes in construction, combination and arrangement of parts may be made without departing from the spirit and scope of the invention as claimed. 10

Having thus described the invention, what I claim is:

In a device of the character described, an

auxiliary clothes line adapted to have articles secured thereto for spaced suspension relative to each other, a plurality of clasp type suspension members engageable with the auxiliary clothes line at spaced intervals and providing therein kinks acting to separate the articles from each other, and a carrying member including a bar insertible through the suspension members and a ball portion integrally and flexibly connected with one end of the bar and provided with a keeper to engage the other end of the bar whereby the suspension members may be threaded on and off said bar and prevented from accidentally sliding off said bar when the latter is engaged with said keeper.

MARIE COLEMAN.
